UNITED STATES PATENT OFFICE.

BENJAMIN H. KUNKEL, OF LEMOYNE, PENNSYLVANIA.

DESIGN FOR A NECKTIE.

50,752.

Specification for Design.

Patented May 8, 1917.

Application filed March 16, 1917. Serial No. 155,338. Term of patent 7 years.

To all whom it may concern:

Be it known that I, BENJAMIN H. KUNKEL, a citizen of the United States, residing at Lemoyne, in the county of Cumberland and State of Pennsylvania, have invented a new, original, and ornamental Design for a Necktie, of which the following is a specification, reference being had to the accompanying drawing, forming part thereof.

Copies of this patent may be obtained for five cents each, by addressing the "Commissioner of Patents, Washington, D. C."

The figure is a plan view of the necktie, showing my new design.

I claim:

The ornamental design for a necktie, as shown.

BENJAMIN H. KUNKEL.
